UNITED STATES PATENT OFFICE.

ARTHUR A. ABBOTT, OF CHICAGO, ILLINOIS.

SIDE-BAR VEHICLE.

SPECIFICATION forming part of Letters Patent No. 333,271, dated December 29, 1885.

Application filed July 27, 1885. Serial No. 172,804. (No model.)

To all whom it may concern:

Be it known that I, ARTHUR A. ABBOTT, a citizen of the city of Chicago, in the county of Cook and State of Illinois, have invented a 5 certain new and useful Improvement in Side-Bar Vehicles, of which the following is a full, clear, and precise description thereof, reference being had to the annexed drawing of the same, making part of this my specification.

10 The figure is a perspective view of the same, showing the relations and the adaptations of the parts covering the form of my invention.

In said accompanying drawing, A represents the ordinary axle, which may be of any 15 suitable form. B is the fifth-wheel thereof. C is the side bar.

D represents a part of the fifth-wheel, and E E are the two parts, respectively, of the head-block attached to the fifth-wheel and 20 formed in one piece with the two side bars.

The object of my invention is the construction of a simple, powerful, and durable device, not heretofore existing in analogous structures of this character. The ordinary side-bar-vehicle gear is composed of several parts, one 25 end of each side bar being attached to the rear axle, and the other to the head-block, with a connecting attachment of the head-block with the fifth-wheel over and connected to the front axle. The objection to this construction is the speedy loosening of the clips connecting the different parts, owing to their position and manner of connecting; and, further, the side bars and head-blocks must be constructed 30 of wood, as iron cannot be firmly clipped to iron, and the wood is liable to destruction by wear and breakage, and is at all times uncertain, unless constructed of such dimensions as to be impracticable in use and for sale, as 35 strength of structure and lightness of appearance are the two desirable results to be obtained.

I am also aware that a continuous metal side bar in one piece has been constructed, connecting the front and rear axles by a U-shaped formation; but this construction has the disadvantage of being more expensive, difficult of formation, requiring more expensive material, and preventing the utilization of the material which can be incorporated in 50 my device.

In my invention I construct a side-bar gear 45 ing made of iron in two parts, one side bar and one-half of the head-block being formed together as one piece, and the two side bars 55 and partial head-blocks so formed are firmly united to the fifth-wheel in the usual position, the rear ends of the side bars being attached to the hind axle. This construction is thus 60 more cheap and effective than any heretofore employed, permits of easier replacement of any 65 parts destroyed by accident or wear, permits the utilization of material otherwise worthless, takes less material, and admits of substantial 70 latitude of connection between each side bar and the fifth-wheel.

I am aware that it has been proposed to 75 make the side bars and head-block of the vehicle of one continuous piece of metal. I do not claim this construction; but

What I claim is—

As a new article of manufacture, a side-bar-buggy gear in two parts, the two side bars being of metal, forming the head-block in said two parts, meeting at or near the center of the 75 front axle, in combination with the front and rear axles and fifth-wheel of the vehicle, substantially as shown and described.

ARTHUR A. ABBOTT.
